(57) **CLAIM**

The ornamental design for a tool pod housing, as shown.

DESCRIPTION

FIG. 1 is a front view of a tool pod housing showing our new design;

FIG. 2 is a rear view thereof;

FIG. 3 is a top view thereof;

FIG. 4 is a bottom view thereof;

FIG. 5 is a left side view thereof; and,

FIG. 6 is a right side view thereof.

The broken lines shown in the figures are for environmental purposes only and form no part of the claimed design.
